Garettoon Smith & Henry Brown, of Philadelphia, Pa:

Assignors to

Leibrandt, ~~Mc~~ Dowell & Co. of the same place.

Letters Patent No. 962. Dated Oct. 20th 1857.

~~~~~
The schedule referred to in these Letters Patent & making part of the same.

To all whom it may concern,

Be it known, that we Garettoon Smith and Henry Brown, both of the City of Philadelphia and State of Pennsylvania, have invented or produced a new and original design for a parlor stove termed the Halcyon, and we do hereby declare the following to be a full, clear and exact description of the same, reference being had to the accompanying drawing and to the letters of reference marked theron.

The annexed drawing represents in perspective a view of our ornamental parlor (Halcyon) stove.

- A. is the bottom plate of the stove
- B. the front plate with ornamental doors a. a. the back plate being similar in design with the exception of the fire doors, and ash pit opening.
- C. the top plate.
- D. the sun with its cover.
- E. one of the side plates, the opposite side plate being exactly similar.

We claim the combination and arrangement of ornamental figures and forms represented, forming together an ornamental design for parlor stove.

In testimony whereof we have signed our names to this specification, before two subscribing witnesses.
